UNITED STATES PATENT OFFICE.

JOHN HERRON, OF MARQUETTE, MICHIGAN.

LOCOMOTIVE-SMOKE-BOX TRAP-DOOR.

1,287,310.

Specification of Letters Patent. Patented Dec. 10, 1918.

Application filed April 24, 1917. Serial No. 164,138.

To all whom it may concern:

Be it known that I, JOHN HERRON, a citizen of the United States, residing at Marquette, in the county of Marquette and State of Michigan, have invented new and useful Improvements in Locomotive-Smoke-Box Trap-Doors, of which the following is a specification.

This invention relates to trap doors fitted to the spark-arresting screens of locomotive smoke boxes, and its object is to provide a novel and improved support and fastening for such a door, whereby the same is easily and quickly applied, securely held in place, and readily removed.

The object stated is attained by means of a combination and arrangement of parts to be hereinafter described and claimed, and in order that the same may be better understood, reference is had to the accompanying drawing forming a part of this specification.

In the drawing, Figure 1 is a vertical section showing the application of the invention; Fig. 2 is a front elevation; Fig. 3 is an enlarged vertical section on the line 3—3 of Fig. 2; Fig. 4 is an enlarged vertical section on the line 4—4 of Fig. 2, and Fig. 5 is an end view of a latch.

Referring specifically to the drawing, 10 denotes the smoke box of a locomotive into which the exhaust nozzle 11 extends as usual. The smoke box contains a spark-arresting screen 12 supported in any approved manner and having an opening which is fitted with a removable trap door. In this opening is mounted a door frame composed of angle bars 13 which are set with one of their flanges 14 outstanding from the opening. The door is composed of a frame covered with a netting 15, the frame being composed of top and bottom bars 16 and 17, and side bars 18, these bars being angle irons. The netting is bolted or otherwise fastened as shown at 19 to one of the flanges of the angle irons, and the latter are so positioned as to leave one of their flanges outstanding. The door seats at its sides in the angle of the side bars of the door frame 13, and at the top and bottom in the angle of the top and bottom bars of the door frame. To the outstanding flange of the top bar of the door frame is fastened an angle bar 20 positioned so that one of its flanges is downturned and opposite the other flange of the top bar of the door frame. The door frame is therefore of a channeled construction at

the top, and the top of the gate seats loosely in this channel and is shorter than the door frame so that it may be pushed upwardly a short distance. To the outstanding flange 60 of the bottom bar of the door frame is also fastened an angle bar 21 arranged in the same manner as the angle bar 20 to provide a channel for the reception of the bottom edge of the door.

A latch is provided for holding the door closed, said latch comprising the following parts:

To the outstanding flange of the bottom cross bar 17 of the door is fastened an outstanding bracket arm 22 which is offset downwardly from said flange to bring its bottom flush with the outstanding flange 14 of the door frame bottom bar. To this offset portion of the bracket arm, on the under 75 side thereof, is pivoted, by a bolt or rivet 23, a latch bar 24 of such length that one end may be swung to come beneath the aforesaid flange 14, the other end of the latch bar being upturned as shown at 25 to form a 80 hand-hold. This end of the latch bar is adapted to be locked to the bracket arm by a pin or other suitable device 26 when the latch bar is in holding position. The end of the latch bar engaging the flange 14 is bevelled at its sides to obtain a tightening effect.

To remove the door, the pin 26 is removed and the latch bar 24 is swung clear of the bottom flange 14 of the door frame, which releases the door, so that it may now be lifted bodily to clear the guard bar 21, after which it is dropped down to clear the top guard bar 20, which completes the operation. The bottom guard bar 21 is in two spaced sections to provide a recess 27 to accommodate the latch bar. As the door seats at an angle to the center line of the smoke box and the boiler, it is of itself prevented from falling out of the door frame by the top and bottom guard bars. The top guard bar not 100 only acts as a stop for the door, but also prevents cinders from clogging the channel in which the top of the door seats, which would prevent the easy removal of the door. The manner in which the door is set in the 105 frame makes a tight joint, and the door can be easily removed and replaced. The structure is also strong and durable, as well as simple and relatively inexpensive.

While the preferred embodiment of the 110 invention has been shown, it will be understood that various changes and modifica-

tions in the structural details may be made without a departure from the spirit and scope of the invention as claimed herein-after.

5 I claim:

1. In a door structure, a frame composed of top, bottom and side angle bars set with one of their flanges outstanding, angle bars connected to the outstanding flanges of the top and the bottom bars and positioned to locate one of their flanges opposite to and in spaced relation with the other flanges of said top and bottom bars, to produce channels at the top and the bottom of the frame, and a door seating at its side edges in the angle of the frame side bars, and at the top and the

bottom in the aforesaid channels, said door being shorter than the frame and movable bodily in the direction of its length out of the channels for removal from the frame. 20

2. The combination with a door and its frame, of an outstanding bracket arm carried by one end of the door, a pivoted latch bar carried by the bracket arm and engageable with an adjacent portion of the door frame, the latter having an outstanding flange beneath which the latch bar is adapted to be swung, and means for locking the latch bar to the bracket arm. 25

In testimony whereof I affix my signature. 30

JOHN HERRON.
